UNITED STATES PATENT OFFICE.

FOSTER MALIC POOLE, OF TULSA, OKLAHOMA, ASSIGNOR TO THE BROWN INSTRUMENT COMPANY, OF PHILADELPHIA, PENNSYLVANIA, A CORPORATION OF PENNSYLVANIA.

TUBE-STILL REGULATION.

Application filed July 28, 1925. Serial No. 46,515.

The general object of the present invention is to provide an improved method of, and improved means for regulating the operation of tube oil stills; and the invention is characterized by the fact that the supply of heat to the still is made dependent on the temperature of the oil passing through the still at a point in its path of travel at which the oil is somewhat below the maximum or still exit oil temperature.

By making the operation of the furnace dependent on the oil temperature at an intermediate point in the path of oil travel through the still instead of on the temperature at which the oil leaves the still, as has been done heretofore, certain important practical advantages are obtained. For one thing variations in conditions of operation requiring compensating changes in the rate of heat supply create significant changes in oil temperature more quickly at a point in the path of oil travel at which the oil temperature is appreciably below that of the exit temperature of the oil, than at the oil exit. Any decrease in the time interval between a change in oil temperature and the compensating change in the rate of heat supply obviously and desirably minimizes the exit oil temperature fluctuations.

The location of the thermocouple or other temperature responsive controlling means in a portion of the path of oil flow in which the temperature is appreciably below the exit temperature of the oil, is advantageous also because it eliminates or minimizes difficulties of control caused by carbon deposits insulating the thermocouple or other thermo-sensitive control device from the temperature to which it is intended to respond.

The various features of novelty which characterize my invention are pointed out with particularity in the claims annexed to and forming a part of this specification; but for a better understanding of the invention, its advantages, and specific objects attained with its use, reference should be had to the accompanying drawings and descriptive matter in which I have illustrated and described a preferred embodiment of my invention.

Of the drawings:

Fig. 1 is a diagrammatic representation of an oil still; and

Fig. 2 is an enlarged view of a portion 55 of the apparatus shown in Fig. 1.

In Fig. 1, I have diagrammatically illustrated a conventional form of oil tube still comprising a furnace housing A, the upper portion of the interior of which is traversed 60 by a bank of horizontally disposed tubes B, which are located above a combustion chamber A', and between the latter and a stack outlet A² for the escape of the spent heating gases. The tubes B are shown as connected 65 by external return bends B' and B² to cause the oil to flow in series through tubes A at successively lower levels from an upper oil inlet pipe C to a lower oil outlet pipe D. The still is heated by the combustion of oil or 70 gas supplied under suitable pressure through a burner pipe E at a rate dependent on the adjustment of a control valve E'. As shown, air for combustion is drawn by the stack suction into the combustion chamber 75 A' from the external atmosphere through the opening A³ in the furnace housing through which the burner pipe E projects into the combustion chamber. It will be understood that the apparatus as above described embodies no part of the present invention, but on the contrary constitutes merely one typical form of tubular oil still 80 with which the invention may be employed with advantage.

In accordance with the present invention, the regulating valve E' is opened and closed in automatic response to the temperature of the oil at a point in its path of travel through the still intermediate the inlet C 85 and the outlet D, and preferably in most cases where the oil temperature is nearer the oil exit than the oil entrance temperature. To this end, in the particular form of apparatus illustrated by way of example, the return bend B² is formed with a well or tubular casing B³ extending into its oil passage to receive a thermo-sensitive device F, which ordinarily is a thermocouple. The terminals of the device F are connected to a 90 suitable control instrument G. The latter may be an indicating or recording galvanometer with control provisions of known form as shown, for example, in the patent to Brown No. 1,355,448, granted October 12, 100 1920, for a reversible relay motor operated valve actuating mechanism H for adjusting the valve E'. The mechanism H may be of

the known type shown by the patent to Egard and Wilhjelm, No. 1,397,680, granted November 22, 1921. As diagrammatically illustrated, the motor of the mechanism H is energized from current supply conductors 1 and 2 in the direction required to give an opening movement to the valve E' and thereby increase the fuel supplied to the combustion chamber A', when a temperature reduction in the return bend B² causes the instrument G to connect the motor terminal 3 to the supply conductor 2. Conversely when the temperature in the return bend B² increases above normal the instrument G connects the motor terminal 4 to the supply conductor 2 and the valve E' is then adjusted to reduce the rate of fuel supply to the chamber A'.

I is a thermo-couple or other thermometric device provided as is usual for measuring the still oil exit temperature. As shown, the device I is inserted in a thermometer well J between the still oil outlet proper, and the still delivery pipe O.

With the well B³ containing the control thermo-couple F located at a point at which the oil temperature is below the still exit temperature, carbon deposits on the outer wall of the well B³ may or may not occur depending on the conditions of operation, but if carbon does deposit on the wall B³ such deposit will in practice always be less than the simultaneously formed deposit on the outer wall of the well J. Carbon deposits on the walls of the thermometer wells B³ and J tend, of course, to make the thermometric devices in said wells indicate lower temperatures than the actual temperatures of the oil in contact with the respective wells. In consequence the errors, if any, in the indications of the instrument G due to carbon deposits will be less with the instrument G responsive to the temperature in the well B³ than if responsive to the temperature in the well J. The existence of errors in the indications of an instrument connected to a thermo-couple "i" due to carbon deposits on the well J can be detected and their extent approximated by an ordinary skilled attendant by comparing the normal differential, that is, the differential at the start of the run, of the temperature in the well J and the temperature in the well B³, with the present differential. If the temperature in the well B³ remains constant and the differential is less, other factors remaining the same, the operator can assume that the temperature at J is being indicated incorrectly due to carbon deposits approximately by the amount of difference

between the normal differential and the present differential. When the errors due to carbon deposits on the well J are thus approximated (it is this temperature which must be kept constant and determines the efficiency of the run), it is a simple matter to effect an approximate compensation for such errors by means of the adjusting provisions with which the control instruments like the instrument G are automatically provided. As a net result the location of the thermocouple to which the control instrument G is responsive to the well B³ instead of in the well J, permits longer runs or periods of still operation between the inevitably necessary shut-downs for carbon removal.

Having now described my invention what I claim as new and desire to secure by Letters Patent is:

1. In operating an oil heater of the type comprising tubes connected to form an elongated path of oil travel and means for heating said tubes and thereby progressively heating oil traveling along said path, the method which consists in varying the oil heating effect in inverse response to changes in the temperature of the oil at a point in the path of oil travel through the still intermediate the entrance and exit ends of said path.

2. In operating an oil heater of the type comprising tubes connected to form an elongated path of oil travel and means for heating said tubes and thereby progressively heating oil traveling along said path, the method which consists in varying the oil heating effect in inverse response to changes in the temperature of the oil at a point in the path of oil travel through the still at which the oil temperature is somewhat below the maximum oil temperature attained in the still.

3. An oil heater comprising tubes connected to form an elongated path of oil travel between a heater oil inlet and a heater oil exit, of combustion regulating provisions therefor including a thermo-sensitive device responsive to the temperature of the oil passing along said path at a point thereof at which the oil temperature is intermediate the oil entrance and exit temperatures, and means actuated by said device for increasing and decreasing the still heat supply as the temperature to which said device responds decreases and increases.

Signed at St. Louis, in the county of St. Louis, and State of Missouri, this 21st day of July, A. D. 1925.

FOSTER MALIC POOLE.
